WALTER S. RYAN, OF INDIANAPOLIS, INDIANA, ASSIGNOR TO RYAN CONSTRUCTION COMPANY, OF MUNCIE, INDIANA, A CORPORATION.

CIRCUIT-CONTROLLING SWITCH.

No. 926,681.

Specification of Letters Patent.

Patented June 29, 1909.

Application filed December 2, 1907. Serial No. 404,783.

To all whom it may concern:

Be it known that I, WALTER S. RYAN, a citizen of the United States, residing at the city of Indianapolis, in the county of Marion, State of Indiana, have invented a new and useful Circuit-Controlling Switch, of which the following is a specification.

This invention relates to improvements in switch-mechanisms, and to that type of switch-mechanisms wherein the operation of the switch intermittently is accomplished.

Objects of this invention are to provide a device of the character described which will be inexpensive to install and which will require little or no attention in its operation.

Other purposes are to provide such a device which will be safe in point of fire hazard and will consume a minimum amount of current and whereby a quick-break and clean cut-off of the circuit is accomplished. To these ends my invention consists of the new construction combination and arrangement of parts and details described in this specification, illustrated in the accompanying drawings and pointed out in the claims.

Similar characters of reference refer to corresponding parts throughout the several views in the drawings in which—

Figure 1 is a front view of my invention the receptacle being shown partially in vertical section. Fig. 2 is a plan view thereof, and Fig. 3 is a side view of Fig. 1 the parts all being in normal position. Fig. 4 is a horizontal sectional view on the line 4—4 Fig. 1. Fig. 5 is a vertical central sectional view on the line 5—5 Fig. 3. Fig. 6 is a side view of Fig. 1, the movable parts being translated to extreme opposite position. Fig. 7, is a detached view of contact-spring and contact-strip 50 and 51. Fig. 8 is a detached enlarged sectional view of the receptacle. Fig. 9 and Fig. 10 are diagrammatic views showing two different systems of wiring which are being employed in the utilizing of my invention.

1 designates a solenoid suitably supported and retained in the metallic frame 2 which is rigidly secured by bolts 3^a to the upper portion of the base-plate 3, made of suitable non-conductive material such as slate.

3^r designate holes through which may be passed means to sustain the device in proper position against the object of support.

3^g designates a hole through which are passed the wires to be hereinafter referred to.

4 designates a core-piece which forms the core for the upper portion of the solenoid, (see Fig. 5) and is supported by the frame 2. The bottom of this core-piece has a cone-shaped recess therein and corresponds with the cone-shaped upper end of the core 5. 60 The core-piece 4 fits tightly in the spool 1^d of the solenoid. The insulating disk 1^e is provided to afford protection and insulation for the solenoid-wires 58, 42 and 46 which are connected to the solenoid.

56 and 57 are binding-posts. To secure the solenoid in its proper place in the frame 2 it is passed into position and then the screw 2^d that passes through a suitable hole therefor in the top of frame 2 is screwed into the 70 said core-piece 4 and tightened.

6 designates a connecting-bar retained slidingly in correct position in the guide-bracket 7. This connecting-bar 6 is shouldered and threaded at its ends, its upper end is screwed 75 into the lower end of the core 5 and supports the bridge-bar 8 made of conductive metal and insulated from the core and connecting-rod by the hard-fiber rings 9 and 10. A similar bridge-bar 11 is supported on the lower 80 end of the connecting-bar 6, insulated therefrom by the hard fiber-rings 12 and 13, and is securely retained in its position by the nut 14 that is screwed on the lower end of the connecting-bar, as shown in Fig. 5. Rigidly 85 secured to the base 3 by the bolts 3^a in central alinement with the solenoid 1 is the receptacle 16 adapted to retain a suitable fluid such as mercury, which I have found preferable, upon which a float is disposed as will 90 be hereinafter referred to. Cast-iron has been found a desirable metal for this receptacle.

17 designates a cover-plate of insulating fiber having perforations therein for the passing of the certain members to be hereinafter described.

18 designates a suitable tube having a flared upwardly extending inlet through which the mercury is introduced into the 100 receptacle.

Adapted to reside and move freely within the receptacle and buoyed in the mercury is the float 20, cylindrical in form and of such bulk and weight that the proper buoyancy 105 thereof in the mercury is obtained. Secured in and extending upwardly from the center of the float 20 and through the cover-plate 17

is the rod 21 upon which is secured the head 22, provided with the annular depression 23 into which the cushion 15 is fitted.

24, 25 and 26 are contact posts, upon the 5 lower ends of which are screwed and retained rigidly the fiber-plugs 24^d, 25^d and 26^d. These fiber-plugs are threaded externally so that they may be screwed down to the desired depth and adjustably retained in 10 the threaded holes 20^d provided therefor in the float 20. Each of these plugs has a cup-shaped upper end 30 the function of which will be hereinafter referred to. The float 20 is constructed of such bulk and weight 15 that when it is not detained in the bottom of the receptacle as shown in Fig. 5 by the weight of the supervening parts, it will by its buoyancy ascend to the dotted line position, as shown in Fig. 6.

20 53 designates a contact post positioned on the head 22 said contact-post being threaded and thus capable of vertical adjustment.

28 designates a contact-post, and 29 a resilient contact-strip, both secured to the base 25 3, the latter being below the former and at such position that it will be engaged by the said contact-post 53 carried by the head 22. As the float rises to complete its upward stroke, the resilient contact-strip 29 will be 30 raised and pressed into engagement with the contact-post 28, as shown in Fig. 6.

Carbon-blocks 8^d and 11^d are rigidly secured by the counter-sunk bolts to the ends of the bridge-bar 8 and 11 respectively. 35 Positioned so as to correctly register with these carbon-blocks and the ends of the bridge-bars 8 and 11 respectively, are the carbon-blocks 31^d and 32^d supported by the resilient-strips 31 and 32 respectively. These 40 resilient-strips 31 and 32 and similar resilient strips 31^e and 32^e secured to the base-plate 3 by the binding-posts 33, 34, 35, and 36, and are so formed and adapted that in the operation 45 of my invention, as will be hereinafter described, a proper contact in their engagement and disengagement with the bridge-bars 8 and 11, is obtained.

37 designates a resilient contact member adapted to be engaged by the bridge-bar 11 50 at the limit of its upward movement, the function of which contact member will be apparent hereinafter in the description of the operation of my invention.

59, 60 and 61 designate binding-posts. 55 A given quantity of mercury having been introduced into the receptacle 16 through the tube 18 sufficient to rise to the dotted line 16^d the switch-mechanism is in readiness 60 for operation, and appears as shown in Fig. 1, the float 20 being submerged and held in lowermost position by the weight of the core 5 and its connected parts. The fiber-plugs 24^d, 25^d and 26^d are submerged, and the mercury is in contact with all of the contact- 65 posts 24, 25 and 26. The contact post 53 is

screwed down so as not to engage the contact-strip 29, as these two elements are of use only where my switch-mechanism is arranged in series.

The operation of my invention will be 70 readily understood from the following description, and by reference to the diagrammatic view shown in Fig. 9. A controlling switch 40 being closed, the current enters along wire 140 and 240 and the binding post 41, passes 75 through wire 58 and coil 42 of solenoid 1, thence through wire 43 into contact-post 26, thence through mercury to contact-post 25, wire 44, terminal-post 34 and out over wire 48. The core 5 is influenced and ascends 80 quickly and with such force that the bridge-bars 8 and 11 with their carbon-blocks 8^d and 11^d move up to the contact-strips 31 and 32 with their carbon-blocks 31^d and 32^d, and are brought into close engagement with 85 each other establishing external circuit A. At the same time the bridge bar 11 makes contact with the contact member 37, the function whereof will be presently referred to. There being then no weight resting upon the 90 head 22 the buoyant float 20 immediately but slowly rises, and as it does so, the contact-posts 26 and 25, they being supported in the fiber-plugs 24^d at a height relatively greater than the height of the contact- 95 post 24, emerge from the mercury, then the current that is flowing through the wire 58 flows through the resistance coil 46 of the solenoid (see Fig. 9) thence through wire 45, contact-post 24, mercury, and receptacle- 100 wall 16, wire 47, contact-member 37 and the bridge-bar 11, thence through contact-strip 32, terminal-post 34 and out over wire 48. By this arrangement the quantity of current consumed during the time subsequent to the 105 lifting of the core 5 is greatly reduced, because a very small current is sufficient to maintain the core 5 in its uppermost position. With the continuation in the ascent of the float the contact-post 24 emerges from the 110 mercury thus breaking the remaining circuit through the solenoid, the core instantly drops, and with the disengagement of the bridge-bars 8 and 11 from the contact-strips 31 and 32, and the terminals 33 and 34 115 respectively the external circuit A is opened. By the arrangement of the contact member 37 as shown, the current will flow through the resistance coil 46 so long as the bridge bar 11 is in raised position and will be opened 120 when the bridge bar is released. By having the circuit that includes the resistance coil 46 thus kept normally open, the flow of the current through the external circuit in series with the flow of the current of the circuit 125 through the resistance coil 46, is prevented, and the perfect operation of the solenoid, when the external circuit is closed for use, is assured. The weight of the core and its connected parts resting on the head 22 130

Oper
4700

causes the float to descend and to be submerged in the mercury; the external circuit will remain open until the float will have reached a position where contact-posts 25 5 and 26 are both submerged whence the operation above described will be automatically repeated. Thus the opening and closing automatically of the switch at pre-determined intervals is accomplished positively and reliably.

For obtaining a contact of the mercury with the contact-posts that engage the same, which will at all times be reliable and whereby corrosion of the contact-members may be 10 prevented, I have devised the detail as shown in Fig. 8. The fiber-plugs 24^d, 25^d and 26^d each has its top provided with the cup-shaped recess 30 which forms a cup that will at all times be filled with the mercury, so that 15 the making and breaking of the circuit as hereinbefore described, is accomplished in the mercury, that is, at the meeting of the bulk of mercury with that in the cup, surrounding its contact-post. In the upward 20 movement of the float and the dropping of the mercury and as the fiber-plug rises and reaches the surface, the surface-tension of the mercury is broken instantaneously and simultaneously with the emersion therefrom of 25 the fiber-plug. In the movements of the float and the mercury reverse to those just described the surface-tension about the peripheral edge of this fiber-plug is broken instantly and simultaneously with the submergence 30 of the fiber-plug and the bulk of the mercury unites with that in the cup instantaneously.

Where the accomplishment of the automatic establishing of circuits successively 40 and then the breaking of said circuits simultaneously is desired, my invention is of equal utility and effectiveness. To accomplish the foregoing result a plurality of my improved switches are arranged and wired as plainly 45 appears in the diagrammatic view shown in Fig. 10. When my circuit-controlling switches are thus arranged, the contact post 53^a in the head 22^a is so adjusted that at the limit of the upward movement of the float, 50 the said contact post will make contact with the resilient contact strip 29^a as hereinbefore described. Then the contact-post 24^a, and its fiber-plug 24^d is so adjusted by screwing it down that the said fiber-plug will at all 55 times during the operation of the float, be submerged in the mercury. The controlling switch 40 is closed, the current enters at binding-post 41^a, passes through wire 42^a of solenoid, thence through wire 43^a into contact-post 26^a, thence through mercury into 60 contact post 25^a, wire 44^a, terminal post 34^a and out through wire 48^a. The core 5^a is influenced and ascends quickly and with such force that the bridge-bars 8^a and 11^a contact- 65 strips 31^a and 32^a, and terminal posts 35^a

and 36^a establish the external circuit A¹. There being then no weight upon the head 22^a the buoyant float 20^a immediately rises and as it does so the contact-posts 26^a and 25^a emerge from the mercury, then the current that 70 is flowing through binding-post 41^a passes through the resistance wire 46^a thence through 45^a, contact post 24^a, mercury, receptacle-wall 16^a, wire 47^a, contact-spring 50, contact-strip 51, (which normally are in 75 contact with each other) wire 48^a, contact-member 37^a, contact-strip 32^a terminal post 34^a and out. With the continuation of the ascent of the float the contact post 53^a raises the contact-spring 29^a into connection with 80 contact-strip 28^a whereupon the current is afforded a circuit through the second switch as follows: Binding post 41^b, wire 42^b, wire 43^b, contact post 26^b, mercury, contact post 24^b, wire 45^b, 29^a, contact post 53^a, head 22^a, 85 float 20^a, mercury, receptacle-wall 16^a, wire 47^a, contact-spring 50, contact-strip 51, wire 48^a, contact-member 37^a, contact-strip 32^a, terminal 34^a and out. The core 5^b is influenced and ascends quickly and there is 90 established the external circuit B¹, in the manner as described in establishing external circuit A¹. There being then no weight upon the head 22^b, the buoyant float 20^b immediately and slowly rises and as it does so the 95 contact post 26^b (25^b being not used in this or other added switches) emerges from the mercury, then the current that is flowing through binding post 41^b passes through resistance wire 46^b, wire 45^b, contact-strip 28^a, 100 contact-spring 29^a float 20^a, mercury, receptacle-wall 16^a wire 47^a, contact-spring 50, contact-strip 51, wire 48^a, contact-member 37^a, contact-strip 32^a, terminal post 34^a and out.

With the continuation of the ascent of the float the contact post 53^b raises the contact-spring 29^b to contact-strip 28^b whereupon the current is afforded a circuit through third switch as follows: Binding post 41^c, 110 wire 42^c, wire 43^c, contact-post 26^c, mercury, contact post 24^c, wire 45^c, contact-spring 29^b, contact post 53^b, head 22^b, float 20^b, mercury, contact-post 24^b, wire 45^b, contact-spring 29^a, float 20^a, mercury, receptacle- 115 wall 16^a, wire 47^a, through 50, 51, 48^a, 37^a, 32^a, 34^a and out. The core 5^c is influenced and ascends quickly and there is established the external circuit C¹ in the manner as described in establishing external circuit A¹ and 120 B¹. There being then no weight upon the head 22^c, the buoyant float 20^c immediately and slowly rises and as it does so the contact 125 26^c (25^c being not used in this or other added switches) emerges from the mercury, then the current that is flowing through binding-post 41^c passes through resistance wire 46^c, wire 45^c, contact-strip 28^b, contact spring 29^b, contact post 53^b, head 25^b, float 20^b, contact post 24^b, wire 45^b, contact-strip 130

- 29^a, float 20^a, mercury receptacle-wall 16^a, wire 47^a contact-spring 50, contact-strip 51, wire 48^a contact member 37^a, contact-strip 32^a, terminal post 34^a and out. With a continuation of the ascent of the float the contact post 53^c lifts the contact-spring 50 disengaging it from the contactstrip 51, thus interrupting the circuit through the solenoid 1^a, 1^b, and 1^c, the cores 5^a, 5^b, 5^c, instantly drop, breaking the previously established external circuits A¹, B¹, and C¹ simultaneously. The weight of the cores and their connected parts resting on the heads 22^a, 22^b, and 22^c causing the floats 20^a, 20^b, and 20^c to descend and to be submerged again in the mercury. The said external circuits A¹, B¹, and C¹ will remain open as aforesaid until the floats each will have reached the initial submerged position whence the operation of establishing circuits successively as just described will be automatically and continuously repeated.
- What I claim as my invention and desire to secure by Letters Patent is:
1. In an electric switch, a receptacle, a float therein, a movable member normally resting on said float and depressing the same, an electro-responsive device for moving said member to release the float, a circuit including said electro-responsive device and means controlled by said float for energizing the electro-responsive device when the float is depressed and deenergizing it when the float is released.
  2. In an electric switch, a receptacle, a float therein, a movable member resting on said float and depressing same, an electro-responsive device for moving said movable member to release the float, a circuit including said electro-responsive device, means controlled by the said float for energizing the electro-responsive device when the float is depressed, means controlled by the float to partially deenergize the electro-responsive device and means controlled by the float for completely deenergizing the electro-responsive device, when the float has been released.
  3. In an electric switch, a receptacle, a float therein, a movable member normally resting upon said float and depressing same, an electro-responsive device for moving said movable member to release the float, a circuit that includes said electro-responsive device, means controlled by the said float for energizing the electro-responsive device when the float is depressed and for deenergizing it when the float is released, a resistance element in the said circuit that includes the said electro responsive device, and means controlled by the float to cut in said resistance after the movable member has been moved.
  4. In an electric switch, a receptacle, a float therein, a solenoid the core of which is adapted to normally rest upon and depress said float, a bridging member carried by said core, a circuit that includes said solenoid, a switch operated by the float to cause the said solenoid to be energized when the float is depressed whereby the core and bridging-member are lifted and the float is released, a switch operated by the float to cause the said solenoid to be deenergized during the upward movement of the float.
  5. In an electric switch, a receptacle, a float therein, a solenoid the core of which is adapted to normally rest upon and depress said float, a bridging member carried by said core, a circuit that includes said solenoid, a switch operated by the float to cause the said solenoid to be energized when the float is depressed whereby the core and bridging-member are lifted and the float is released, a resistance element in the said circuit, a switch operated by the float to cut in said resistance after the core has been lifted.
  6. In an electric switch, a receptacle, a float therein, a solenoid the core of which is adapted to normally rest upon and depress said float, a circuit through the solenoid, a switch operated by the float to cause the said solenoid to be energized when the float has been depressed and to be deenergized after the float has been released, a resistance element in the said circuit, a switch operated by the float to cut in said resistance after the core has been lifted, a switch in said circuit adapted to be operated by the bridging member whereby the circuit in which is the resistance element will be normally kept open when the bridging member is not in raised position.
  7. In an electric switch, a receptacle, a float therein, a solenoid the core of which is adapted to normally rest upon and depress said float, a bridging member carried by said core, a main circuit through the solenoid, a pair of contacts for said circuit that are carried by the float, a third contact carried by the float, a fluid conductor between the said pair of contacts and the third contact said pair of contacts being arranged so as to disengage the fluid conductor in the upward movement of the float, and the third contact being arranged so as to momentarily disengage the fluid conductor subsequent to the disengagement aforesaid by said pair of contacts and as the float reaches the upper limit of its movement, a secondary circuit through a portion of the solenoid the fluid conductor and said third contact, a switch that is actuated by the bridging-member carried by the core, so that the said main circuit and secondary circuit are open while the float is being depressed.
  8. In an electric switch, a receptacle, a conductive fluid therein, a float, a solenoid the core of which has secured thereto a downwardly disposed guide-rod connected to said core adapted to normally rest upon and depress said float, a main circuit through the solenoid, a pair of contact-posts for said

- tions, a secondary circuit through a portion of the solenoid, a contact post for said secondary circuit that is mounted on said float and with its fluid contact point at a point lower than the other contact-posts, a bridging member carried by the core, a switch adapted to be operated by the said bridging-member, so 5
5 that the said main circuit and secondary circuit are open while the float is being depressed.
9. An electric switch of the kind described including a solenoid a receptacle disposed vertically beneath said solenoid, a fluid conductor in said receptacle, a float disposed within said receptacle and on the said fluid conductor, there being a cushion on the head of said float, a guide way supported underneath the said solenoid a guide rod secured to the bottom of the core of the solenoid mounted movably in said guideway the said solenoid and receptacle being so placed with reference to each other that there will be a substantial distance between the head of the float and the bottom of the guide bar when each is at its uppermost position, substantially as described.
10. A multiple switch comprising a plurality of switch mechanisms each including a receptacle, a float therein, a movable member to rest on and to normally depress said float, an electro-responsive device, a circuit in which said electro-responsive device is included, a secondary circuit a resistance element therein, contacts operated by the float to energize the electro-responsive device when the float is depressed and to cut into the said secondary circuit the resistance after the float is released, means controlled by 15

- the float of the last switch-mechanism after its float is released.
11. A multiple switch comprising a plurality of switch mechanisms each including a receptacle, a float therein, a movable member to rest on and to normally depress said float, an electro-responsive device, a circuit in which said electro-responsive device is included, a secondary circuit a resistance element therein, contacts operated by the float to energize the electro-responsive device when the float is depressed and to cut into the said secondary circuit the resistance after the float is released, means controlled by the float of the initial and each intermediate switch-mechanism to cause the current of the circuit to flow through the next switch mechanism after the float of the predecessor has been released, a switch in the secondary circuit that stands normally closed adapted to be opened by the float of the last switch-mechanism after its float is released, means to open the secondary circuit after the floats have been so released including a switch in said secondary circuit arranged so as to be opened by the movable member of the initial switch mechanism.
- In testimony whereof, I have hereunto signed my name to this specification in the presence of two subscribing witnesses.
